UNITED STATES PATENT OFFICE.

STANLEY LEECH AND GRANVILLE LEECH, OF DETROIT, MICHIGAN.

WRINGER.

Application filed December 2, 1921. Serial No. 519,310.

To all whom it may concern:

Be it known that we, STANLEY LEECH and GRANVILLE LEECH, subjects of the King of Great Britain, residing at Detroit, in the county of Wayne and State of Michigan, have invented certain new and useful Improvements in Wringers, of which the following is a specification, reference being had therein to the accompanying drawings.

10 In the operation of clothes wringers of the roll or roller type wherein one of the rolls or rollers is under spring pressure or tension and both the rolls or rollers are driven to cause clothes, fabrics and other matter to pass between the rolls or rollers, indurate objects, as buttons or pins, are often encountered resulting either in injury to the rolls or the clothes, or else the progress of the clothes is retarded. Then again, in 15 feeding clothes and fabrics to the rolls the fingers or sleeve are sometimes caught between the rolls, resulting in injury particularly to the fingers. In either instance, it is essential to immediately release the roll or 20 rolls under tension and for this purpose various quick release devices have been invented.

This invention relates to a quick release device for a tensioned or spring pressed wringer roll, and the primary object of our invention is to provide such a device that besides being used to quickly release the tension or pressure on a wringer roll may also be used to increase the tension or pressure on the wringer roll, the device being simple, durable and readily accessible to the operator of a wringer.

Another object of this invention is to furnish a wringer of the roll type with roll separating means by which a tensioned or spring pressed roll may be quickly separated from another roll, and such means contributes to an expeditious operation of the quick releasing device of the wringer.

45 A further object of our invention is to accomplish the above results and numerous advantages by a construction that will be hereinafter described and then claimed, and reference will now be had to the drawing wherein

Figure 1 is a front elevation of the wringer, partly broken away and partly in section;

Fig. 2 is an enlarged horizontal sectional view taken on the line II-II of Fig. 1;

Fig. 3 is a similar view taken on the line III-III of Fig. 1;

Fig. 4 is a perspective view of the quick release of the wringer, and

Fig. 5 is a vertical sectional view taken on the line V-V of Fig. 1.

In the drawing, the reference numeral 1 denotes a hollow one-piece wringer frame having depending parallel bifurcated or slotted side arms 2 and 3, said arms having the lower ends thereof open so that spindles 4 and 5 of rolls 6 and 7 respectively may be placed in the arms 2 and 3. The rolls 6 and 7 are of a conventional wringer type and the spindles 4 and 5 have gear wheels 8 adapted to mesh, while the spindle 5 has a protruding end 9 that may be provided with a detachable crank or to which a suitable source of power may be connected. The gear wheels 8 are preferably inclosed by a casing 10 integral with the arm 2 and when the spindle 9 of the roll 7 is driven, the roll 6 is rotated in an opposite direction from the roll 7, so that clothes may be moved between said rolls or backed therefrom.

The spindle 5 of the roll 7 is supported on bearings 11 mounted in the arms 2 and 3, and between the spindles 4 and 5 are roll separating means, preferably in the form of coiled expansion springs 12 which are adapted to elevate the spindle 4 of the roll 6 relative to the spindle 5 of the roll 7.

Engaging the spindle 4 of the roll 6 are bearings 13 and engaging said bearings are the ends of a bowed spring 14 having its middle portion fulcrumed or loosely mounted in a head 15 loose on the lower end of a spring tensioning rod 16, the lower end of the rod 16 being rotatably held in the head 15.

Suitably attached to the top of the frame 1 is a threaded sleeve 17 through which the rod 16 extends. On the upper end of the rod 16 is a head 18 and adjacent said head is a transverse pin 19.

Adjustable on the threaded sleeve 17 is a screw member or nut 20 provided with a cap 21 through which the rod 16 extends and said cap has opposed handles 22 by which the screw member can be easily rotated or turned in either direction. The cap 21 has an upper wall provided with a transverse slot 23 which permits of the transverse pin 19 passing in and out of the cap when said pin is correctly positioned, and

walls 24 of said slot constitute shoulders or abutments against which the ends of the transverse pin 19 may impinge. In the cap 21 are other shoulders or abutments 25 adapted to engage the pin 19, said shoulders or abutments being spaced from the slots 23 by lateral recesses 26, said recesses having beveled walls 27 permitting of the ends of the pin 19 easily riding into and out of the recesses 26.

As shown in Fig. 1, the main spring 14 is under tension holding the roll 6 in proximity to or against the roll 7, with the springs 12 under tension. The main spring 14 may be placed under additional tension by turning the screw member 20 in a clockwise direction, because the shoulders 25 of the cap 21 engage the ends of the transverse pin 19.

20 Should it be desired to quickly release the tension of the spring 14 and permit the springs 12 to separate the rolls 6 and 7, the screw member 20 is turned or partially rotated in a counterclockwise direction. This 25 may be accomplished by quickly striking either one of the handles 22. When either handle is struck a blow to turn the screw member in a counterclockwise direction the shoulders 25 are carried away from the ends 30 of the transverse pin and the shoulders 24 brought into engagement with the ends of said pin. This movement of the cap 21 places the transverse slot 23 thereof in vertical alinement with the transverse pin 19 35 and the pin 19 can be projected out of a slot by the rod 16 being elevated by the spring 14.

To again establish a driving relation between the screw member 20 and the rod 16, the head 18 is depressed until the transverse pin 19 enters the transverse slot 23,

and then by partially turning the rod 16 in a counterclockwise direction, the ends of the transverse pin 19 are carried under the beveled walls 27 and into the recesses 26 to abut the shoulders 25. Then by turning the screw member in a clockwise direction the main spring 14 may be placed under tension.

It is thought that the operation and utility of our quick release device for wringers will be apparent without further description, and while in the drawing there is illustrated a preferred embodiment of our invention, it is to be understood that the structural elements are susceptible to such change, in size, shape and manner of assembling, as fall within the scope of the appended claim.

What we claim is:—

Means for placing the main spring of a wringer under tension and quickly releasing such tension, comprising a rod having a transverse pin, a stationary threaded sleeve through which said rod extends, a screw member on said sleeve, and a slotted cap carried by said screw member and under which the pin of said rod engages to hold said spring under tension, said cap member having shoulders adapted for engagement by the rod pin to establish a driving relation with said rod, said screw member when rotated in one direction imparting movement to said rod and when rotated in an opposite direction releasing said rod.

In testimony whereof we affix our signatures in presence of two witnesses.

STANLEY LEECH.
GRANVILLE LEECH.
